UNITED STATES PATENT OFFICE.

RICHARD D. GALLAGHER, JR., OF NEW YORK, N. Y., ASSIGNOR TO STANDARD COUPLER COMPANY, OF NEW YORK, N. Y., A CORPORATION OF NEW JERSEY.

DRAFT AND BUFFING RIGGING.

SPECIFICATION forming part of Letters Patent No. 690,265, dated December 31, 1901.

Application filed August 26, 1901. Serial No. 73,289. (No model.)

To all whom it may concern:

Be it known that I, RICHARD D. GALLAGHER, Jr., a citizen of the United States, residing at New York, in the county of New York and State of New York, have invented certain new and useful Improvements in Draft and Buffing Rigging; and I do hereby declare the following to be a full, clear, and exact description of the same, reference being had to the accompanying drawings, forming a part of this specification, and to the figures of reference marked thereon.

This invention relates to improvements in rigging designed to yield and take up strains of parts moved by heavy pressure, the type of rigging being well exemplified in my prior patent, No. 677,654, and in my contemporaneous applications, Serial Nos. 73,287 and 73,288.

The present invention is designed as an improvement upon the structures set forth in the above-mentioned patent and applications, the invention, however, being applicable to any draft-rigging involving the use of friction elements having wedging friction-faces for causing a movement of one of the elements with relation to the other.

The invention consists, broadly stated, in forming the friction-faces which coöperate in giving the relative movements of the elements in the form of spirals or curving about an axis, whereby the structure may be conveniently made in cylindrical form and the strains distributed more uniformly in parts better adapted to withstand such strains than in corresponding parts as heretofore constructed.

The invention consists, further, in certain novel details of construction and combinations and arrangements of parts, all as will be hereinafter described, and pointed out particularly in the appended claims.

Referring to the accompanying drawings, Figure 1 is a longitudinal section through a rigging embodying the present improvements. Figs. 2, 3, and 4 are perspective views of the friction elements of the structure shown in Fig. 1. Fig. 5 is a view corresponding to Fig. 1 and showing a somewhat different arrangement of the friction elements. Fig. 6 is a section on the line xx , Fig. 5. Fig. 7 is a sectional view showing a reverse

arrangement of the elements shown in Fig. 6. Fig. 8 is a sectional view on the line yy , Fig. 7. Figs. 9 and 10 are sectional views, Fig. 9 being one-half in elevation and showing reverse arrangement of modified forms of friction elements. Fig. 11 is an end elevation, looking into the structure shown in Fig. 9, with the follower-plate and one of the wedge members removed. Fig. 12 is a perspective view of one of said wedge members. Fig. 13 is a side elevation of still another form of rigging, the internal arrangement of the friction elements being shown partly broken away and in section and partly in dotted lines; and Figs. 14, 15, 16, and 17 are views of said elements. Fig. 18 is a diagrammatic projection of the elements, showing their relative arrangement and coöperation. Fig. 19 is a sectional view illustrating still another arrangement of the elements; and Figs. 20, 21, 22, and 23 are views of such elements, Fig. 21 being an end elevation of the elements shown in Fig. 19 with two of the wedge-blocks removed. Fig. 24 is a diagrammatic projection of one-half of the device, illustrating the relative arrangement and action of the elements of the structure illustrated in Fig. 19.

Like numerals of reference in the several figures indicate the same parts.

In carrying the present invention into practice and with a view of permitting of the utilization of circular casings and circular arrangements of elements said elements are formed with their friction-faces spiral or conforming to spirals about a common axis. With such an arrangement of the friction-faces it is obvious that one or more of the elements will travel around the axis in the operation of the parts, and it is also obvious that, broadly, this arrangement of the friction-faces may be carried into effect with a large number of different structures. For instance, the friction-faces of the elements described in my before-mentioned patent and applications may be projected in the form of spirals or arranged about a common axis, so as to secure the advantages incident to such an arrangement and as claimed herein.

Referring particularly to Figs. 1, 2, 3, and 4, it will be seen that the draft-bar and its

yoke or strap, (numbered 1 and 2,) which members will be hereinafter referred to as the "pressure-transmitting" member, coöperate with follower-plates 3 3, between which follower-plates the yielding pressure-resisting member or spring 4 and the friction elements themselves are arranged. In the form illustrated in the figures referred to the friction elements consist of a wedging member and two coöoperating members. The wedging member is operated upon by one of the other members and in turn itself operates upon the third member, so as to advance the third member in proportion to the advance of the wedging member and the movement imparted thereto by the first member. This general proposition follows true in all the forms illustrated in the accompanying drawings; but in the particular figures under consideration the wedging element 5 is formed with right and left spirals 6 and 7, respectively, one of said spirals being located within or being of less diameter than the other. The outer one, 8, of the coöoperating elements is provided with a spiral friction-face 9, adapted to coöperate with the spiral friction-face 7 of the wedging element, and the other element, 10, is provided with a spiral friction-face 11, adapted to coöperate with the spiral friction-face 6 of the wedging element. Said elements 8 and 10 are adapted to move longitudinally one within the other and are held against relative rotation by a key or spline 12, working in a corresponding keyway or groove. With such an arrangement it is obvious that if the wedging element be moved inwardly and one of the coöoperating elements be held against such movement the other element will be advanced by reason of the action of the spiral faces more rapidly than the inward movement of the wedging element. In the construction shown the element 8 is in the form of a casing which incloses the spring 4, while the element 10 rests against the forward end of said spring, and consequently if the wedging element 5 be moved inwardly by buffing strains applied to the follower-plate 3 or the pressure-transmitting element itself, against which said wedging element may rest, said wedging element will be driven inwardly, and sliding with a rotary motion down the incline 9 will advance the element 10 against the tension of the spring 4, and by reason of the friction of said faces and the wedging action of the parts will vastly augment the resistance of the spring 4. Strain in an opposite direction applied to the rear end of the casing 8 will cause a similar movement and compression of the spring 4 by forcing the element 10 rearwardly. The element 10 may be termed the "follower," and it is obvious that the arrangement may be duplicated at both ends of the rigging, if so desired, in which instance the spring would be confined between two followers 10 instead of between one of said followers and the rear follower-plate 3, as illustrated in Fig. 1. To provide for a limited direct compression of the spring, whereby

preliminary or minor strains may be absorbed by said springs without bringing the friction elements into action to augment the power of the spring, the casing 8 or its equivalent, which forms a stop for one of said elements, may have a limited free longitudinal play—as indicated, for instance, by the space 13—between the rear end of the casing 8 and the follower-plate 3 at the rear end of the rigging.

It will be understood, of course, that the follower-plates or their equivalent elements are adapted to be mounted between the draft-timbers or other car-framing, as is usual in apparatus of this type, and such parts of the draft-timbers or car-framing as indicated diagrammatically in the drawings at 14. Should wear occur between the friction-faces of the elements, it is obvious that it may be compensated for by adjusting the elements 8 and 10 with respect to each other, as, for instance, by providing a series of keyways for the key 12, as will now be described in connection with Figs. 5 and 6. In said Figs. 5 and 6 the right and left spirals are made in the form of threads upon the interior and exterior of an element 15, against which the spring 4 abuts. Coöperating with the interior spirals of the member 15 are coöperating spiral inclines 16 on an element 17, which is adapted to be advanced by the pressure-transmitting member under pressure in one direction or to be held against movement when pressure is applied in the other direction. Coöperating with the exterior spirals of the element 15 is the spiral 18 of the element 19. The elements 17 and 19 are held against independent rotation, but permitted to move longitudinally with respect to each other by means of keys and keyways 20, which may, if desired, be arranged in successive order around the entire interior of the casing 21, which forms a part of or is connected to move with the element 17. The opposite end of the spring abuts against a follower 22, which follower 22 is connected with the element 19 by shoulders 23, whereby said spring may be put under compression by a movement of said element 19 toward the left in Fig. 5. Longitudinal movement of the element 15 in a direction to compress the spring is prevented by a stop or support 24, which, however, preferably has a limited movement for direct compression of the spring, as before explained, and which stop for convenience may abut against a follower-plate 25 at the rear end of the rigging. The element 17 may be connected with the casing 21 by a series of keys and keyways 26, Fig. 6, whereby it may be adjusted in its rotary position. In operation pressure applied to the element 17 advances the same and causes a rotation of the element 15, inasmuch as said element 15 cannot advance farther than the limited movement before referred to, and by the rotation of said element 15 (which element constitutes a wedging member) the element 19 is moved reversely and compresses the spring 4 from the rear end. Under pres-

sure applied in the opposite direction to the follower-plate 25 the preliminary movement will be applied directly to the spring through the follower 22; but when said follower-plate 25 comes in contact with the support 24 and advances the wedging element 15 the latter will be caused to rotate by reason of its engagement with the spiral 16 and in so rotating it will advance the element 19 more rapidly, thereby compressing the spring in the same direction as in the first instance.

The structure shown in Fig. 7 corresponds closely to that shown in Fig. 1, save that the spirals instead of being formed on the forward face of the wedging member are formed on the interior and exterior surface, respectively, of the same and the inner coöperating member is held against longitudinal movement and the outer coöperating member moves longitudinally to compress the spring. In said Fig. 7 the numeral 27 indicates the wedging member, having on its interior face spiral inclines 28 and on its exterior face spiral inclines 29. The inclines 28 coöperate with corresponding inclines on an element 30, having an extended pin or support adapted to abut against a follower-plate 32 to prevent longitudinal movement of said element 30, save to a limited extent, for the purpose before explained. Surrounding the wedging element 27 is another coöperating element 33, having interior inclines or spirals coöperating with the inclines 29, and the spring 4 is confined between the element 33 and the follower-plate 32. The two elements 30 and 33 are held against rotation with respect to each other by keys and keyways formed on the stem 31 and lower portion of the element 33, as indicated at 34 in Fig. 8; but said elements are free to move longitudinally with respect to each other. With such construction pressure applied to the follower-plate 3 advances the friction elements as a body until the movement of the element 30 is arrested, when if a farther advance takes place the wedging member 27 is caused to travel down the incline on the member 30 and by its rotation advances the element 33 more rapidly or at a differential speed with respect to the follower-plate 3 and other wedging elements, thereby compressing the spring and augmenting the resistance by the friction and wedging action of the inclines.

In Figs. 9 and 10 structures are shown wherein the wedging member is divided into two parts movable with respect to each other, and it is obvious that said wedging member may be divided into as many parts as desired, and the inclines on said parts may be arranged to oppose the rotation of the coöperating elements, whereby a balance in rotative effort is secured and no special provision for preventing the rotation of said other coöperating elements with respect to each other need be provided.

Referring to Fig. 5, the elements 35 and 36 correspond to the elements 8 and 10, respec-

tively, in Fig. 1; but instead of a single incline or spiral being formed on each of said elements there are two spirals or inclines 70 formed on each of said elements and arranged in opposite directions—that is to say, on each element there is a right and left spiral. Wedging elements (illustrated in perspective in Fig. 12 and numbered 37) are provided with right 75 and left spiral inclines 38 and 39, and these right and left spiral inclines coöperate with the spiral inclines on the elements 35 and 36. Two of the wedging elements 37 are provided, and the inclines are so arranged that the wedging elements rotate toward and from each other when moving in one direction or in the other, as will be readily understood from Fig. 11, where one of said elements 37 is shown in position and the position of the other is indicated by the dotted line 40, and said elements move under the influence of pressure in the direction of the arrows in said Fig. 11, sliding down the inclines 41 on the element 36 and forcing the element 35 forwardly by coöperating with the incline 42 thereon, as will be readily understood. The element 36 is supported by the casing 43, adapted to abut against the follower-plate 44, corresponding to the follower-plate 3 of Fig. 1, and the wedging members 95 preferably rest against a follower-plate 45, corresponding to the other of said follower-plates 3 in Fig. 1, and a limited play is allowed between the casing 43 and follower 44 for direct compression of the spring under minor strains. The operation is in all respects similar to the operation of the device illustrated in Fig. 1, save that by the employment of a divided wedging member the two portions of said member exert equal but opposing rotative efforts on the coöperating members and so counteract any tendency of said members to rotate with respect to each other.

In Fig. 10 the construction of the friction element is similar to that described and illustrated in Fig. 9 and the same numerals of reference are applied thereto; but in this figure the inner element 35 is held against longitudinal movement by a supporting-stem 46, and the spring is confined between the outer element 36 and the rear follower-plate 44. The operation is similar to that before described, save that the outer one of the friction elements is advanced to compress the spring instead of the inner one.

In Figs. 13 to 18, inclusive, a structure is shown wherein the wedging member is provided with oppositely-directed inclines and the coöperating elements are provided one with inclines arranged in one direction and the other with inclines arranged in the other direction, while the rotative effort imparted by the wedging member is counteracted by arranging the reverse sides of the inclines so as to abut and move one upon the other longitudinally or in the direction of spring compression. Fig. 17 illustrates the wedging member in perspective, said member being numbered 47, and it is provided with two sets of

oppositely-directed spiral inclines 48 and 49, respectively. The outer coöperating element 50 is provided with two inclines 51, directed downwardly in the same direction—say in the 5 form of a left-hand screw—and the inner coöperating element 52 is provided with two inclines 53, directed downwardly in opposite directions to the inclines 51. The inclines 53 of the inner element are located in the spaces 10 between the inclines 51, Fig. 14, while the stem of said inner element projects through the center of the element 50 into position to engage the spring. The said stem carries at its end a disk or head 52^a, which is preferably mounted thereon, so as to be removable, as shown in Figs. 13 and 15, in order to allow the parts to be assembled with the stem in the central opening 50^a of the member 50. The inclines 48 on the wedging member coöperate with the inclines 53 on the inner coöperating member, and the inclines 49 on the wedging member coöperate with the inclines 51 on the outer coöperating member. The inclines 51 and 53 are formed on projections on 20 the respective members, and the rear faces of said projections are arranged in straight lines and are adapted to contact and slide one upon the other, as indicated clearly at 54 in the diagrammatic illustration Fig. 18. This 25 figure illustrates the relative arrangement and action of the several elements of the device, but does not show the spiral conformation of the friction-faces, being simply diagrammatic in order that the operation will be 30 more readily comprehended. As the member 47 advances it will slide down the incline 51 and force the inclines 53 forwardly, inasmuch as said inclines 53 are prevented from moving in any other direction by the straight 35 faces of the projections at 54, and thus the member 52, upon which the inclines 53 are mounted, will be advanced against the tension of the spring, the member 50 being held against said longitudinal movement by the 40 casing 55, corresponding to the casing 8 in Fig. 1. The same looseness or limited play may be allowed between the casing 55 and rear follower-plate 56 as in the former instances, and the pressure-transmitting member 45 may coöperate with said plate 56 and with a forward follower-plate 57, as heretofore. The structure shown in Figs. 19 to 24, inclusive, corresponds closely to the structure shown in Figs. 13 to 18, inclusive, save that 55 the wedging member is sectional, in which respect it corresponds to the structure shown in Figs. 9 to 12. In said Figs. 19 to 24 the elements which coöperate with the wedging elements are provided with oppositely-directed 60 ed inclines which counteract the rotative effort before referred to, as will be readily understood from the diagrammatic illustration Fig. 24. The wedging element is shown in the form of separate blocks 58, each having 65 oppositely-directed spiral inclines 59 and 60. The outer coöperating element 61 is provided with oppositely-directed inclines 62, adapted

to coöperate with inclines 59 on the wedging elements, respectively, while the inner coöperating element 63 is provided with oppositely-directed inclines 64 and 65, with which the inclines 60 on the wedging elements coöperate. In this form of device the inner element 63 has a limited longitudinal movement, and the spring 4 is confined between 70 the outer elements 61 of the device, there being a duplicate arrangement of the friction elements at each end of the spring. The limitation of the movement referred to may be secured by allowing said inner element 63 to 75 abut against one or the other of follower-plates 66 at each end of the rigging when strains are applied in one direction or the other, and, if desired, the said elements 63 may have inwardly-projecting stems loosely 80 connected by a coupling-pin 67, although this latter construction is optional. In operation inward movement of either of the follower-plates 66 advances the wedging members 58 down the inclines 64 65, thereby displacing them angularly, and by the coöperation of the inclines 59 and 62 the outer coöperating element 61 is advanced against the tension of the spring, said friction elements augmenting by their wedging and frictional 85 resistance the power of the spring to resist buffering or draft strains.

In all the apparatus described the mechanism is double-acting, so to speak—that is to say, it will operate to resist strains in 100 either direction with equal facility—and in every instance the friction elements are arranged in circular sequence and around a common axis, with which construction it is found most convenient and desirable to employ spiral friction-faces, and while I have 105 specifically described a number of different forms of mechanism to which the invention is applied it is to be understood that the invention is capable of a much wider range of 110 application than set forth herein, and hence I do not wish to be restricted to the specific forms illustrated.

Having thus described my invention, what I claim as new, and desire to secure by Letters 115 Patent, is—

1. In a rigging such as described, the combination of the following instrumentalities, to wit; a pressure-transmitting member, a yielding pressure-resisting member and a friction device interposed between said members and embodying three elements movable with relation to each other and two of which coöperate under the influence of the pressure-transmitting member to produce a movement 120 of the third in a direction to compress the yielding member and all of said elements being circularly disposed about a central axis; substantially as described.

2. In a rigging such as described, the combination of the following instrumentalities, to wit; a pressure-transmitting member, a yielding pressure-resisting member and a friction device interposed between said members 130

and embodying three elements each having an inclined friction-face each circularly disposed about a common axis, each movable with relation to the other and two of which 5 coöperate under the influence of the pressure-transmitting member to produce a movement of the third in a direction to compress the yielding member; substantially as described.

3. In a rigging such as described, the combination of the following instrumentalities, to wit; a pressure-transmitting member, a yielding pressure-resisting member arranged in alignment therewith, a friction device embodying three elements movable with relation to each other and two of which coöperate 10 under the influence of the pressure-transmitting member to produce a movement of the third in a direction to compress the yielding member, said elements being circularly disposed about a central axis and a cylindrical inclosing wall; substantially as described.

4. In a rigging, such as described, the combination of the following instrumentalities, to wit; a pressure-transmitting member, a yielding pressure-resisting member arranged in alignment therewith three circularly-disposed friction elements interposed between said members and having coöoperating inclines, one of said elements being movable 25 with the pressure-transmitting member, another with the resisting member and means for arresting the movement of the third of said elements whereby a differential movement of the other two elements is secured; substantially as described.

5. In a rigging, such as described, the combination of the following instrumentalities, to wit; a pressure-transmitting member, a yielding pressure resisting member and a friction device interposed between said members and embodying three elements each having an inclined spiral friction-face, each movable with relation to the other one of said elements 40 engaging the pressure-transmitting member, another the yielding member and the third forming the connection between the two first-mentioned elements and whereby the movement of one is imparted to the other, substantially as described.

6. In a rigging such as described, the combination of the following instrumentalities, to wit: a pressure-transmitting member, a yielding pressure-resisting member, friction elements located between said members and through the relative movement of which elements the movement of one of said members is imparted to the other, said elements having spiral friction-faces through the coöperation 55 of which the movement of one of said elements is imparted to another with means for holding two of said elements against relative rotary movements, while the coöperating element is permitted a rotary movement with relation to said two elements; substantially as described.

7. In a rigging such as described, the combination of the following instrumentalities, to wit: a pressure-transmitting member, a yielding pressure-resisting member, three friction elements interposed between said members, one of said elements having oppositely-directed spiral inclines thereon, and each of the other elements having a spiral incline 70 said inclines coöperating respectively with the spiral inclines on the first-mentioned element; substantially as described.

8. In a rigging such as described, the combination of the following instrumentalities, to wit: a pressure-transmitting member, a yielding pressure-resisting member, friction elements located between said members and embodying a friction element behind which the yielding member is confined, having a spiral-inclined friction-face, a second friction 80 element having an oppositely-inclined spiral friction-face with means for preventing the relative rotation of said elements a third element having oppositely-directed spirally-inclined friction-faces coöperating respectively 85 with the friction-faces on the other elements.

9. In a rigging such as described, the pressure-transmitting member and the yielding pressure-resisting member, of friction elements located between said members for transmitting the movement of one of said members to the other, one of said elements engaging the yielding resistance member and having an inclined spiral friction-face, another of said elements being held against 95 movement with said first-mentioned element and having an oppositely-directed spiral incline thereon and a third element having oppositely-directed inclines coöperating with the inclines on the other elements respectively, whereby differential movement of the elements is secured; substantially as described.

10. In a rigging such as described, the combination with the pressure-transmitting member and the yielding pressure-resisting member, of friction elements interposed between said members, two of said elements having spiral friction-faces, the face on one element inclining in the opposite direction from the 100 face on the other, said elements being keyed together to prevent relative rotary movements and one being held against longitudinal movements when the friction elements are active and a third element having oppositely-directed spiral inclines coöperating with the spiral inclines on the other elements respectively; substantially as described.

11. In a rigging such as described, the combination with the pressure-transmitting member and spring, of a cylindrical casing inclosing the spring and supporting an incline at one end forming a friction element, a second friction element bearing against the spring and having an oppositely-directed incline, 115 and a wedging friction element having oppositely-directed inclines coöperating with the 120

inclines on the other elements and adapted to be moved by the pressure-transmitting member; substantially as described.

12. In a rigging such as described, the combination with the pressure-transmitting member and spring, of two friction elements one nested within the other and having oppositely-directed inclines circularly arranged, one of said elements bearing against the spring, a stop for limiting the movement of the other element and a third element with which the pressure-transmitting member co-operates having oppositely-directed inclines co-operating respectively with the inclines on the other elements; substantially as described.

13. In a rigging such as described, the combination with the pressure-transmitting member and spring, of two friction elements one nested within the other and having oppositely-directed spiral inclines, one of said elements bearing against the spring, a stop for limiting the movement of the other element, and a third element with which the pressure-transmitting element co-operates having oppositely-directed spiral inclines co-operating respectively with the spiral inclines on the other elements; substantially as described.

14. In a rigging such as described, the combination with the pressure-transmitting member and spring, of a friction element bearing against said spring and having a spiral incline thereon, a second friction element inclosing the first and having an oppositely-directed spiral incline, a third friction element having oppositely-directed spiral inclines thereon, and follower-plates co-operating with the opposite end of the spring and last-mentioned friction element and a support extending from the last-mentioned frictional element into proximity to the follower-plate at the opposite end of the spring; substantially as described.

15. In a rigging such as described, the combination with a buffering-spring and a draw-bar, of friction elements interposed between said spring and draw-bar, said elements having

friction-faces circularly arranged and being movable as a body during preliminary spring compression and a stop for arresting the movement of one of said elements whereby they are given movements with relation to each other during the final spring compression; substantially as described.

16. In a rigging such as described, the combination with a buffering and draft spring, follower-plates and draw-bar and strap inclosing said plates, of friction elements interposed between one end of the spring and one of the plates, one of said elements moving with one follower-plate, one moving with the other follower-plate and one moving with the end of the spring, one of said elements having oppositely-directed inclines thereon and the other two, inclines directed respectively in opposite directions and co-operating respectively with the oppositely-directed inclines on the other element; substantially as described.

17. In a rigging such as described, the combination with the buffering and draft spring, the follower-plate and the draw-bar and strap inclosing said plates, of friction elements interposed between one end of the spring and one of the plates, one of said elements having a cylindrical casing inclosing the spring and extending in proximity to the rear plate, another of said elements bearing against the forward end of the spring and the third element bearing against the forward follower-plate, said elements having co-operating friction-faces whereby a limited direct compression of the spring may be effected under pressure in either direction and said friction elements are operated to augment the spring-resistance during the final compression of the spring under strains in either direction; substantially as described.
